UNITED STATES PATENT OFFICE.

EDWARD ALFRED GRAHAM, OF LONDON, ENGLAND.

DESIGN FOR A LOUD SPEAKER.

Application filed November 13, 1925. Serial No. 15,411. Term of patent 14 years.

To all whom it may concern:

Be it known that I, EDWARD ALFRED GRAHAM, a subject of the King of Great Britain and Ireland, residing at London, England, have invented a new, original, and ornamental Design for a Loud Speaker, of which the following is a specification, reference being had to the accompanying drawing, forming part thereof.

The figure is a perspective view of a loud speaker showing my new design therefor.

I claim:

The ornamental design for a loud speaker as shown.

EDWARD ALFRED GRAHAM.
